CLAIM

The ornamental design for an electronic mosquito swatter, as shown and described.

DESCRIPTION

FIG. 1 is a front perspective view of the electronic mosquito swatter in the folded position;

FIG. 2 is a rear perspective view of FIG. 1;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is a bottom view of FIG. 1;

FIG. 9 is an enlarged view of a portion of FIG. 6;

FIG. 10 is a front perspective view of the electronic mosquito swatter in the expanded position;

FIG. 11 is a rear perspective view of FIG. 10;

FIG. 12 is a rear view of FIG. 10;

FIG. 13 is a front view of FIG. 10;

FIG. 14 is a right view of FIG. 10;

FIG. 15 is a left view of FIG. 10;

FIG. 16 is a top view of FIG. 10;

FIG. 17 is a bottom view of FIG. 10;

FIG. 18 is an enlarged view of a portion of FIG. 12;

FIG. 19 is an enlarged view of a portion of FIG. 13;

FIG. 20 is an enlarged view of a portion of FIG. 14; and,

FIG. 21 is an enlarged view of a portion of FIG. 15.

The broken lines shown on the drawings depict portions of the electronic mosquito swatter that form no part of the claimed design. The broken lines in FIGS. 9 & 18-21 depict

(Continued)

boundaries of the enlarged views of the electronic mosquito swatter and form no part of the claimed design.
